UNITED STATES PATENT OFFICE.

HERBERT E. SMITH AND ARTHUR W. SMITH, OF GLOUCESTER, MASSACHUSETTS.

HUMIDIFIER.

Application filed January 14, 1926. Serial No. 81,326.

This invention relates to a humidifier for dwelling houses, buildings and other structures which are provided with a heating plant or apparatus for heating the same.

5 The invention has for its object to humidify the heated air within the house or other building in a highly efficient and economical manner.

To facilitate description, the invention will 10 be described in connection with the heating plant of a dwelling house. The heating plant may be a hot water or steam heater, a hot air furnace or a stove or range, and will be hereinafter referred to as a heater.

15 In accordance with this invention, the waste heats in the products of combustion passing out of the heater to the chimney are utilized for vaporizing water or other liquid which is discharged into the atmosphere 20 within the building to humidify said atmosphere.

To this end, a container for the water or other liquid is subjected to the waste heats in the products of combustion passing through 25 the smoke outlet pipe of the heater to the chimney, and is provided with a vapor outlet which communicates with the atmosphere outside of the smoke outlet pipe, and preferably communicates with a pipe which may be 30 led to any desired part of the building to discharge the vapor therein and thereby humidify the air in the building.

The liquid container is preferably located 35 in a casing capable of being inserted into the smoke outlet pipe to form a section or part thereof.

The liquid container is preferably connected with the vapor outlet pipe by a chamber having flexible walls, and may and preferably will be connected with a water supply pipe, and provision will preferably be made for automatically controlling the supply of water to the container, as will be described.

45 The casing or pipe for the water container may and preferably will be provided with detachable heads, to enable the humidifier to be used with smoke outlet pipes of different sizes or diameters.

These and other features of this invention 50 will be pointed out in the claims at the end of this specification.

Fig. 1 is a longitudinal section of a humidifier embodying this invention;

55 Fig. 2, an end elevation of the humidifier shown in Fig. 1, looking toward the right and with parts in section;

Fig. 3, an enlarged detail in section, taken on the line 3—3, Fig. 1;

Fig. 4, an enlarged detail of the yielding support for one end of the liquid container, 60 and

Fig. 5, a detail of the valve-operating arm to be referred to.

Referring to the drawings, *a* represents a casing which is constructed so as to be capable of forming part of the smoke outlet pipe 65 of a heater, not shown, as it may be of any suitable or well-known type.

For the purpose of this invention, the casing *a* may represent the smoke outlet pipe, 70 and will be referred to as the smoke outlet casing.

The casing *a* may and preferably will be composed of a cylindrical sheet metal member or body portion 10 fitted upon flanges 12 of 75 cast iron heads 13, 14. The heads 13, 14 are provided with openings 15, 16 and with outwardly projecting flanges 17, 18 surrounding said openings, and over which the ends of adjacent sections of a smoke outlet pipe of standard or relatively large size may be fitted.

In the present instance, the flanges 17, 18 have cooperating with them cap members 19, which are detachably secured to the flanges 17, 18, so that cap members having openings 150, 160, and flanges 170, 180 of different sizes may be used with smoke outlet pipes of smaller sizes or diameters than the openings 15, 16.

The smoke outlet casing *a* has co-operating 90 with it so as to be heated by the heat passing through the smoke outlet pipe to the chimney, a liquid container *b*, which in the present instance is shown as located in the casing *a* as is preferred.

The liquid container *b* communicates with the atmosphere outside of the casing *a*, and preferably as herein shown with a pipe, by means of which the vapor may be discharged into the atmosphere at any point desired, either adjacent to or remote from the casing, where it is desired to humidify the atmosphere.

In the present instance, a preferred construction of container is shown, which consists of a sheet metal vessel 20 provided with a sheet metal cover 21 which is hermetically sealed to the vessel 20 at the rim thereof by folding the edge portion of the cover about a flange 22 on the vessel 20.

105 The cover 21 is provided with an opening 110 with which cooperate threaded rings or nip-

5 ples 23, 24 located above and below the cover and serving to clamp the cover to the bottom wall or member 25 of an expansible chamber 26, whose top wall or member 27 is clamped by a threaded nipple or ring 28 to the lower end of a pipe 30, which is extended into and outside of the body portion 10 of the casing *a*.

10 The top and bottom members 27, 25 of the expansible chamber 26 are hermetically sealed together at their outer edges by folding the edge portion of one member about the edge portion of the other as herein shown or in any other suitable manner, and co-operate to form a chamber having flexible walls or diaphragms and which chamber will be hereinafter referred to as the diaphragm chamber.

15 It will thus be observed that the liquid container *b* is yieldingly connected with the pipe 30 by the diaphragm chamber 26 which provides for a fluid-tight connection between the movable container and the stationary pipe 30. The pipe 30 is extended through an opening in the body portion of the casing *a* and is firmly secured to the latter, which may be effected as herein shown.

20 To this end, the pipe 30 is provided on its outer circumference between its ends with an annular flange 32 with which co-operates a clamping ring 33 located on the outside of the body portion 10 of the casing, and which is secured to said flange by screws 34 extended through the said body portion.

25 The pipe 30 forms the vapor outlet for the liquid container.

30 The pipe 30 may be made of any desired length to reach the point at which the vapor is discharged into the atmosphere, but it is preferred to make said pipe relatively short as herein shown and as a casting and to provide an extension 35 which may be ordinary pipe.

35 In the present instance the pipe 35 is represented as a substantially short straight pipe which is of sufficient length to extend up through the floor 36 of a dwelling house and discharge into a room on the first floor of said house, the heater being located in the cellar as now commonly practised. The upper end 40 of the pipe 35 may be protected from injury and stoppage by a cap 37 supported above the floor by a bracket 38 secured to the floor, said cap also acting as a distributor or spreader.

45 With the apparatus as thus far described, water or other liquid to be vaporized, may be manually supplied to the container *b*, but it is preferred to automatically replenish the liquid in the container.

50 In the present instance, one construction is shown for this purpose. To this end, the outlet pipe 30 is provided with an opening 39 which is closed by a plate or wall 40 having a port or opening 41 extended through it.

55 The port 41 has co-operating with it a needle valve 42 which is supported by a metal

70 cage 43 having suitable openings for the passage of water, and said valve is moved in one direction by a spring 44 encircling it between the wall or plate 40 and a collar 45 on said valve.

75 The end of the needle valve which projects through the cage 43 has co-operating with it a set screw 46 carried by an upright arm 47 rigidly attached to the ring 24 and thereby to the container to move with the latter.

80 The liquid container *b* is supported to pivot or turn like a lever, which is effected as herein shown by a bow or yoke-shaped lever having a substantially horizontal front portion 48, and side portions 49, which extend under the rim of the container at the front end and sides thereof and upon which said rim rests, and said side portions 49 have extended upwardly therefrom arms 50 provided with pivot pins or projections 250 (see Fig. 2) 85 which turn in recesses in the upper surfaces of supporting arms 51, preferably integral with the head 13, and extended into the body portion 10 of the casing *a*.

85 The rear end of the container *b* is yieldingly supported by a spring 52 encircling a screw 53 extended through the cover 21 of the container and through the body portion 10 of the casing, said screw having nuts 54 for adjusting the compression or strength of the spring 52, so as to cause the container to assume a substantially horizontal position when the needle valve 42 is closed and the desired quantity of liquid has been admitted into the container.

90 The spring 52 and the nuts 54 are protected by a cap 56 which is suitably secured to the casing *a*, and which supports a device for indicating when the container is empty.

95 The indicating device is shown as a pin or rivet 57 extended through the cap and made of sufficient length to co-operate with the screw 53 to be elevated thereby when the container is empty or the water level therein has fallen below a predetermined point.

100 The indicating device is provided in the present instance with a head 58 located outside of the cap 56 and serving to limit the movement of the pin into the cap, and said device is provided with a washer 59 on its inner end to limit the upward movement of the indicator.

105 The valve or seat 40 co-operates with an opening 60 in a shell or casing 61 (see Fig. 3) containing a strainer or cylinder of wire mesh 62 open at its opposite ends and communicating with a water inlet port 63 at one end of the shell or casing 60 and also with a sediment outlet pipe or pet cock 64 at the opposite end of the said shell or casing.

110 The water inlet port 63 is designed to be connected with a supply of water, which may be the water supply system of the house or building in which the heater is located. The strainer 62 is preferably fitted over the inner

end of the pet cock 64 so as to be removed therewith when it is desired to clean the strainer.

The vapor outlet pipe 30 may be provided with a V-shaped passage in one wall thereof, one branch 70 being open outside of the pipe and the other branch 71 being open inside thereof as shown in Fig. 1. This passage constitutes an overflow for the liquid in case of accident to the valve 42.

The operation of the humidifier herein shown may be briefly described as follows:—

After the casing *a* has been connected with the smoke outlet pipe of the heater, and the vapor outlet pipe 30 has been connected with the room in the house in which the vapor is to be discharged, water is admitted into the container through the filter or strainer casing 61, port 41 and pipe 30.

As the water accumulates in the container, the spring 52 is compressed and when the desired quantity of water has been admitted to cause the container to assume a substantially horizontal position as shown in Fig. 1, the needle valve 42 is at such time closed and the supply of water is automatically shut off.

The waste heat from the heater which passes to the chimney through the smoke outlet pipe of which the casing *a* forms a part, vaporizes the water in the container, and the vapor thus formed passes from the container through the outlet pipe 30 and the extension 35 thereof and is discharged into the atmosphere at the point desired, which as herein shown, is the room on the first floor of the house.

As the water in the container is vaporized, the container becomes lighter and the spring 52 lifts the rear end of the container and causes the latter to turn on the pivots 150 and thus move the valve-operating arm 47 so as to allow the needle valve 42 to be opened by its spring 44 and permit water to flow into the container to replenish the same until the normal quantity has been supplied to the container. As the water accumulates in the container, the weight of the same turns the container in the opposite direction and causes the arm 47 to close the valve 42 when the desired quantity of water has been admitted to the container.

When the container has been restored to its substantially horizontal position, the needle valve 42 is closed and the water supply is shut off until more water is required in the container.

While it may be preferred to provide for automatically controlling the supply of water to the container, it is not desired to limit the invention in this respect, as the container may be supplied manually from time to time.

It will be observed that the water in the container is vaporized by the waste heat from the heater, and that the vapor thus formed is discharged into the atmosphere at the place

desired, and in the case of a house, factory or other building having more than one room, the vapor may be discharged into as many rooms as desired by providing a pipe for each room.

By means of a humidifier of the character herein shown and described, the vapor may be discharged at the place where it is most needed, namely, where the air is dry, and in this manner a desired or normal humidity in the room may be obtained with the attendant beneficial and hygienic effects, to wit: avoidance of winter rash on the exterior surface of the body, irritation of the mucous membrane of the throat and nose, and excessive evaporation from the skin.

While we have shown a preferred construction of apparatus, it is not desired to limit the invention to the particular construction shown.

What is claimed is:

1. A humidifier of the character described, comprising a casing having heads provided with openings, a rigid pipe extended into said casing, a liquid container located in said casing and provided with a vapor outlet, and a chamber having flexible walls interposed between and connected with said container and said rigid pipe.

2. A humidifier of the character described, comprising a casing provided with a vapor outlet pipe, a liquid container located in said casing and communicating with said outlet pipe, a valve controlling the supply of liquid to said container through said vapor outlet pipe, and means responsive to movement of said container for operating said valve.

3. A humidifier of the character described, comprising a smoke outlet casing provided with an outlet pipe having a fluid inlet, a strainer casing communicating with said pipe through said fluid inlet, a strainer in said casing, a valve cooperating with said fluid inlet, a liquid container located in said smoke outlet casing and communicating with the outlet pipe for said casing, and means responsive to movement of said container for operating said valve to supply fluid to said container through said outlet pipe.

4. A humidifier of the character described, comprising a casing having a vapor outlet pipe, a liquid container located in said casing and provided with a vapor outlet, a chamber between said vapor outlets provided with flexible top and bottom walls having vapor outlets, and means for securing said top and bottom walls to the liquid container and to the vapor outlet pipe for said casing to connect the said outlet pipe with said container through said chamber.

5. A humidifier of the character described, comprising a casing having a vapor outlet pipe, a liquid container located in said casing and provided with a vapor outlet communicating with the said vapor outlet pipe, a valve

controlling the flow of liquid into said outlet pipe and container, a pivoted yoke to support one end of said liquid container, and an arm movable with said container and extended into said vapor outlet pipe and co-operating with said valve to operate it.

6. A humidifier of the character described, comprising a casing having a vapor outlet pipe, a liquid container located in said casing and provided with a vapor outlet communi-

cating with said vapor outlet pipe, means for pivotally supporting said container near one end thereof, and means for yieldingly supporting the container near the other end thereof.

15

In testimony whereof, we have signed our names to this specification.

HERBERT E. SMITH.
ARTHUR W. SMITH.
